CARD STACKING MECHANISM

Olaf L. Cleven, Washington, D. C.

Original application July 28, 1939, Serial No. 286,976. Divided and this application December 29, 1939, Serial No. 310,193

19 Claims. (Cl. 271—87)

(Granted under the act of March 3, 1883, as amended April 30, 1928; 370 O. G. 757)

This invention relates to mechanism for stacking cards such as are used in tabulating or other like machines.

The invention may be manufactured and used by or for the Government of the United States for governmental purposes without the payment to me of any royalty thereon, in accordance with the provisions of the act of March 3, 1883, as amended April 30, 1928 (ch. 450, 45 Stat. L. 467).

This application is a division of my application Serial No. 286,976 filed July 28, 1939 for tabulating machines. So much of the illustrations of the present case are taken from the former application as are considered necessary to illustrate the card feed and stacking mechanism in connection with the mechanism with which it is associated in one form in said application.

The invention has the following objects: To simplify the work of retrieving the cards after passing through the machine; to provide a flexible magazine receiver for the cards that will keep a large or smaller number of cards in their proper order; to prevent the cards from sliding on their edges in the receiver, by providing a sliding bottom support for the cards; to provide means to discontinue the feeding of the cards when the receiver is nearing its full capacity; to prevent the machine from feeding cards if the receiver or magazine is not correctly placed to receive and stack the cards in proper order.

In the drawings—

Figure 1 is a rear elevation of a tabulating machine showing the chute for guiding the cards and the feed rolls for bringing them to the stacking mechanism, shown in connection with such machine.

Figure 2 is a horizontal sectional view taken along line 2—2 of Figure 1 showing the stacker mechanism, the receiver magazine and the electrical control for making and breaking the motor circuit under certain conditions, and

Figure 3 is a top plan view of the mechanism shown in Figure 2, illustrating the arrangement of the stacker and receiving magazine, the outline of the base and side plates being shown in dot-and-dash lines.

Referring to Figure 1, the numeral 226 designates a table which forms the base of a tabulating machine. On this base two main side plates A are mounted and between these the inner side plates B are mounted. The plates A form the bearings for the driving mechanism and

card feed of the machine, and the side plates B carry the chute 297 and the feed rolls and gears that convey the cards to the receiving magazine.

The card K of Figure 2 is controlled by feed rolls 293 and 293'. When leaving these last feed rolls a card passes to the revolving stacker 299 mounted on shaft 300. This shaft is journaled in brackets 301 and 302 secured to the under side of the base 226. The stacker is driven from the gear 288 through two idlers 303 and 304, the latter meshing with the gear 305 fastened to shaft 300. As shown, these last mentioned idlers are mounted on a bracket 306 loosely mounted on shaft 300 on one side of the machine only, the lower end of said bracket having a bearing on shaft 304, and is secured in place by screw 306 through the bracket 301.

Referring to Figure 3 particularly, the base 226 and side plates A are shown in dot-and-dash lines showing the outline of the table and side plates to show the relative position of the stacker mechanism and the receiving magazine, which is below the table and arranged obliquely to its side edges. This oblique arrangement is for the purpose of facilitating the withdrawal of the drawer without disturbing the operator's position at the front of the machine.

The receiving magazine about to be described may more conveniently be called a drawer, although it has not the usual sides and rear end that characterize a drawer, but it is operated as such in that it may be pulled out.

The brackets 301 and 302 are extended below the shaft 300 and each is provided with a projection 307 upon which is supported a cross-bar 308. The brackets are further extended to form journals for a shaft 309 (Figure 2) to which shaft two drums 310 are fastened and on these drums metallic ribbons 311 are wound, which ribbons have one end attached to the drums and the other to the drawer at 311' so as to form a part of the bottom of the drawer.

Referring to Figure 3, the numeral 312 designates two flat bars arranged parallel to each other but oblique to the side plates. At the front end of the drawer the bars are attached to studs 313 secured to the under side of the table, and at their rear ends are attached to the cross-bar 308, which bar extends substantially throughout the width of the machine. Between these bars 312 and in the same plane are two other bars 314 secured at their forward ends to the front plate 315 of the drawer, there being provided on the drawer a drawer-pull 316. Centrally located

between these bars and parallel therewith is a rod 317 having therein a lengthwise groove 318 shown in dotted lines in Figures 2 and 3. The forward end of this rod is supported by and rests in the drawer front 315, there being on the rod a wing knob 319 by which the rod may be rocked for a purpose that will presently appear.

The numeral 320 (Figure 2) designates a bracket which is practically the same length as the card, and to the center of which and integral therewith is a slidable sleeve 321 through which the rod 317 passes, aided by rollers 322, and in which it is supported, it being understood that the bracket 320 integral with the sleeve extends laterally in both directions and rests and travels on the stationary bars 312. Pivoted to the sleeve 321 is a lever 323 having an elongated opening embracing the rod 317, there being at the end of the opening a tooth 324 arranged to grip the rod normally on its bottom to prevent retrograde movement of the sleeve 321 and the card stack 327 and to enter the groove 318 in the side of the rod when the wing knob 319 is turned to release the tooth from the rod at such time when it is desired to open the drawer, there being a spring 325 tending to cause the tooth to normally grip the rod in order to prevent the spring tensioned ribbon from moving the sleeve toward the stacker 299. When the rod is turned by the knob 319, the groove 318 will be presented to the tooth 324 of lever 323, which now releases its grip upon the rod and permits it to move sufficiently to close the gap between the card stack 327 and flange 326 carried by the rod, when the drawer is pulled out, thus assuring that the cards are kept in proper upright position. The semicircular flange 326 engages a card stack 327 only when the drawer is pulled out to prevent the cards from falling out of the order in which they have been stacked. The end of rod 317 is further provided with a plug 328 adapted to enter between the spring contact points 329 carried by the block 330 of insulating material, the arrangement being such that when the drawer is pulled out the motor circuit 329' leading to source of current is broken and the machine stopped. There is a manually operated switch C' in series with the motor 356 for use when the operator desires to stop the machine. When the drawer reaches its full capacity the motor circuit is automatically broken, and when it is desired by the operator to remove the drawer before its capacity has been reached, the circuit is also automatically broken, thus preventing the cards from being fed into the drawer when out of position to receive them.

The numeral 331 indicates a backing plate for the cards, which plate is firmly secured to the bracket 320 (Figure 2), and between this plate and bracket are secured the ends of the metallic ribbons 311. These ribbons form the base for the card stack, so that at no time in their travel are the cards moved relatively to their base in suchwise as to injure their edges as might interfere with their future use.

The forward ends of the ribbons 311 are connected to the bracket 320, as shown at 311', and their rear ends are connected with the spring tension drums 310, and there is no connection between the ribbons and the rod 317. Consequently, when a card is added to the stack by the stacker cooperating with the stack, the stacker moves the stack forward a distance equal to the thickness of the card and the ribbons will be moved the same distance, thus presenting a

new part of the ribbon base or support to the added card. As the cards are added one by one to the stack, the stack and bracket 320 and sleeve 321 will slide slowly along rod 317, retrograde movement of the sleeve and parts carried thereby being prevented by the bite of the tooth 324 against the bottom of the rod 317. The stacker is so geared and timed that it will receive a card for each half revolution and by the reason of the eccentric formation of the parts 333' of its arms that form the pockets, will successively stack the cards. A stationary circular casing 334 (Fig. 1) carried by bracket 302 contains a spiral spring, the outer end of which is fastened to the casing and the inner end is secured to the shaft, whereby a constant tension is put upon the metallic ribbons and bracket 320 urging them rearwardly, thus keeping the peripheral portions 333'' of the arms of the stacker in contact with the cards stacked.

The chute 297 is open at its upper and lower ends and at its sides, and, properly positioned at its sides and between its ends are a number of feed rolls that pick up and carry the cards through the chute to the point of delivery to the receiving drawer. At the upper end of the chute adjacent its mouth and on each side is a combined feed roll and gear 282', (Figs. 1 and 2) each formed with an integral gear which meshes with similar gears which form a part of lower feed rolls 282. The lower rolls are driven by the gear 281 mounted on suitable studs on the side plates B, which latter gear 281 is driven by any suitable gearing with the main drive of the machine. The chute is cut away at intervals at its sides to let in the various feed rolls that convey the cards through the chute. The gears of the combined gears and feed roll 282 mesh with idler gear 283 which drive combined gears and rollers 284; the idler 285 is driven by the gears 284; the idler 285 drives the combined gears and rolls 286 which drive the larger idlers 287, which in turn drive the combined gears and rolls 288. All the rolls and gears just described are mounted on studs on the side plates B. The combined feed rolls 282' are mounted on bell-crank levers 289 connected to similar bell-cranks 291 by springs 290. This bell-crank 291 carries combined gears and rolls 292 cooperating with the gears and rolls 284. Further down on the chute are similar bell-cranks 293 and 294 connected by springs 295, which bell-cranks respectively carry combined rolls and gears 296 and 296', which respectively cooperate with combined rolls and gears 286 and 288. Suitable studs as shown, are provided on the side plates B for the mounting of these bell-cranks. The springs 290 and 295 obviously urge their gears and rolls toward their associated rolls with sufficient force to feed the cards through the chute to the base of the machine, and through an opening 298 to the stacking mechanism and the card receiver.

I claim:

1. In a mechanism for handling and stacking cards, in combination, a stacker hopper having an opening to receive the cards, a movable bottom support for supporting the cards in edge-wise position, a rotary stacker arranged to engage the last card in the stack to move said stack and its support toward the outlet end of the hopper, means for rotating the stacker and means for constantly urging the card support and cards stacked thereon toward the stacker with the last card of the stack in engagement with said stacker whereby the movement of the stacker moves the

stack and its support toward the outlet of the hopper as the size of the stack is increased.

2. In a mechanism for handling and stacking cards, in combination, a stacker hopper having an opening to receive the cards, a movable bottom support for supporting the cards in edgewise position, a rotary stacker arranged to engage the last card in a stack to move said stack and its support toward the outlet end of the hopper, means for rotating the stacker, means for constantly urging the support and cards stacked thereon toward the stacker with the last card of said stack in engagement with said stacker, whereby the movement of the stacker moves the stack and its support toward the outlet of the hopper as the size of the stack is increased, and means actuated when the hopper has reached its capacity to stop the rotation of the stacker.

3. In a machine for handling and stacking cards, in combination, a hopper having an opening to receive the cards in substantially vertical position, means for maintaining the cards in stacked position, means for individually stacking the cards in the hopper, and bottom support for the cards and movable in a substantially horizontal direction, the movement of the support being controlled by a card stack as the same increases in size.

4. In a machine for handling and stacking cards, in combination, a hopper having an opening to receive the cards in substantially vertical position, means for maintaining the cards in stacked position, means for individually stacking the cards in the hopper, a bottom support for the cards and movable in a substantially horizontal direction, the movement of the support being controlled by the card stack as the same increases in size, and means for preventing retrograde movement of the cards apart while the cards are being stacked.

5. In a machine for handling and stacking cards, in combination, a chute positioned to receive the cards, means for feeding the cards through the chute, a hopper located at the outlet end of the chute, means within the hopper for individually stacking the cards therein in substantially vertical position, and a bottom support for the cards movable in a substantially horizontal direction and whose movement is controlled by the card stack as it increases in size.

6. In a machine for handling and stacking cards, in combination, a hopper, means within the hopper for individually stacking the cards therein in substantially vertical position, and a bottom support for the cards movable in a substantially horizontal direction and whose movement is controlled by the card stack as it increases in size.

7. In a machine for handling and stacking cards, in combination, a hopper, means for feeding the cards into the hopper individually and stacking the cards therein in substantially vertical position, and a bottom support for the cards moving in a substantially horizontal direction and whose movement is controlled by the card stack as it increases in size, a means for urging said support normally toward the stacking means, and means independent of said urging means to prevent retrograde movement of the movable supporting means.

8. In a machine for handling and stacking cards, in combination, a hopper, means for feeding cards to said hopper, means within the hopper for stacking cards individually therein, a movable support for the cards, a member extending for

substantially the length of the hopper, means slidably mounted on said member for supporting the cards in substantially vertical position, means carried by said member for normally completing an electric circuit, and both manually and automatically operable to control the starting and stopping of the machine.

9. In a machine for handling and stacking cards, in combination, a hopper, having an opening to receive the cards, means within the hopper for stacking the cards individually therein, a horizontally movable bottom support for the cards whereby the cards are moved from the rear to the front of the hopper and controlled by the card stack as it increases in size, a member extending substantially the entire length of the hopper, means slidably mounted on said member for supporting the cards in substantially vertical position, means carried by said member for normally completing an electric circuit, and automatically operated when the size of the stack has reached the capacity of the hopper to break the circuit and stop the machine, and manually operable short of the capacity of the hopper, to also stop the machine.

10. In a machine for handling and stacking cards, in combination, a hopper, having an opening to receive the cards and rotary stacker formed with a peripheral portion arranged to engage the cards for accurately positioning them in the hopper, a bottom support for the cards and movable in substantially a horizontal direction, and whose movement is controlled by a card stack as said stack increases in size, and means connected with the said movable bottom support for constantly urging said support and the card stack normally toward the stacker.

11. In a machine for handling and stacking cards, in combination, a hopper, having an opening to receive the cards, a movable support in said hopper for supporting the cards in substantially vertical position, a rotary stacker arranged to engage the last card in the stock to move said stack and its support toward the outlet of the hopper, said movement of the stack and its support being controlled by the size of the stack as the same is increased.

12. In a machine for handling and stacking cards, in combination, a hopper, means for conveying cards into said hopper in substantially vertical position, a movable bottom support for supporting the cards, whose movement is controlled by the size of the stack as it increases in size, a stacker including means for receiving and adding the cards to the stack in substantially vertical position, means carried by the stacker for engaging the last card in a stack to move the stack and its support toward the outlet end of the hopper, and means for keeping the card stack in constant engagement with the stacker whereby upon the movement of the stacker the card stack and its support are moved toward the hopper outlet.

13. In a machine for handling and stacking cards, in combination, a hopper, having an opening therein to receive the cards, a movable card support for supporting cards in edgewise position, means for maintaining the cards in substantially upright position, a rotary stacker, said stacker being formed with pockets to receive the cards in edgewise position and having eccentric portions on one side of the pockets, and outer concentric peripheral portions, the eccentric portions operating to feed the cards to the stack and the peripheral portions operating against

the last card in the stack to move said stack and its support toward the outlet end of the hopper, means for constantly urging the stacked cards and their support toward the stacker.

14. In a machine for handling and stacking cards, in combination, a hopper, having an opening therein to receive the cards, means for individually stacking the cards in said hopper, a bottom support for the cards comprising spring restrained members movable toward and from the outlet end of the hopper, a slidable rod having a sleeve slidable thereon, means carried by the sleeve for supporting the card stack in substantially upright position, a rotary stacker cooperating with the stacked cards to move said stack and its support along said rod, and electrical contact means carried by the rod cooperating with contacts in a motor circuit, to break said circuit and stop the machine when the hopper has reached its capacity by reason of the addition of the cards to the stack by the stacker.

15. In a machine for handling and stacking cards, in combination, a hopper, having an opening therein to receive the cards, means for individually stacking the cards in the hopper, a bottom support for the cards comprising spring restrained members movable toward and from the outlet end of the hopper and cooperating with the stacker to move the support and the cards stacked thereon toward the outlet of the hopper, a slidable and a rockable rod having one end available on the outside of the hopper, electrical connection between said rod and a motor circuit whereby when the rod is moved toward the outlet end of the hopper the motor circuit is broken to stop the machine, a member slidable on said rod and connected with the card support, means carried by said slidable member for preventing retrograde movement of the card support, said means comprising a pivoted lever having a projection normally engaging the periphery of the rod, said projection being arranged to enter the groove in the rod when said rod is rocked to permit the rod and parts carried thereby to be withdrawn from the hopper to gain access to the cards before the hopper has reached its capacity.

16. In a machine for handling and stacking cards, in combination, a hopper, means for delivering cards to said hopper one after another, means for moving said cards forwardly step by step in substantially vertical position, a circuit for an electric motor whereby the machine is operated, and means associated with said hopper for opening the motor circuit at any point within the range of the capacity of the hopper and thereby stopping the machine.

17. In a machine for handling and stacking cards, in combination, a hopper, means for delivering cards to said hopper one after another at a predetermined speed, means for moving said cards forwardly step by step whereby a definite stack is formed, said means comprising a rotary stacker having a plurality of projections thereon adapted to engage the card last delivered, a means for rotating the portion of the stacker which faces the card at a certain speed corresponding to the speed of delivery means for said card to the hopper, and a movable bottom support for the cards whose advancement is controlled by the card stack as it increases in size.

18. In a machine for handling and stacking cards, in combination, a hopper, means for delivering cards to said hopper one after another, means for moving said cards forwardly step by step whereby a stack is formed, said means comprising a rotary stacker having a plurality of projections thereon adapted to engage the last card delivered, and pockets in said stacker for allowing the card to enter the field of action of the stacker so as to be stacked by the further rotation of the stacker, and a movable bottom card support whose advancement is controlled by the card stack as it increases in size.

19. In a machine for handling and stacking cards, in combination, a hopper, having an opening to receive the cards, a movable card support in the hopper, a rotary stacker in the hopper formed with a peripheral portion arranged to engage the cards for accurately positioning them, the movement of said card support being controlled by the card stack as it increases in size.

OLUF L. CLEVEN.
